CLAIM

The ornamental design for a ceiling fan light glass, as shown and described.

DESCRIPTION

FIG. 1 is a bottom perspective view of a light glass of a ceiling fan;

FIG. 2 is a top perspective view of the light glass of FIG. 1; FIG. 3 is a top view of the light glass of FIG. 1;

FIG. 4 is a bottom view of the light glass of FIG. 1; and, FIG. 5 is a front side view of the light glass of FIG. 1, with rear, right, and left side views being mirror images thereof. The broken lines shown in FIG. 1 illustrate environmental structure. The broken lines shown in FIG. 2 and FIG. 3 illustrate portions of the ceiling fan light glass. None of the broken lines form part of the claimed design.

1 Claim, 5 Drawing Sheets(56)
